Attorney.

UNITED STATES PATENT OFFICE

HOWARD M. WOLF, OF MUNCIE, INDIANA, ASSIGNOR TO THE BRODERICK COMPANY,
A CORPORATION OF INDIANA

STACK FOR PRODUCING FORCED DRAFT

Application filed October 22, 1931. Serial No. 570,374.

Large, portable boilers of the type commonly used in oil fields, for example, must often develop power very much greater than their rated capacities. Thus, a boiler rated 5 at one hundred and twenty-five horse power must frequently develop four hundred horse power. It has heretofore been the practice to provide one hundred and twenty-five horse power boilers with stacks about thirty inches 10 in diameter and thirty-five feet long. Such a stack weighs fourteen hundred pounds or more, and considerable work is required to set up and anchor the stack whenever the boiler is moved, quite apart from the work 15 involved in moving the stack. Even with these large stacks, when the boilers are pushed far above their rated capacities, a forced draft is required. The usual method of effecting the forced draft is to blow steam under a pressure of from 190 pounds to 250 20 pounds into the stack through a three-quarter inch or an inch pipe, thereby consuming from twenty-five per cent to thirty per cent of the steam generated by the boiler.

25 The object of the present invention is to make it possible to operate boilers with comparatively small, light stacks and to blow these stacks, to induce a strong forced draft, with only a small fraction of the steam here- 30 tofore needed for that purpose.

In carrying out my invention I employ a small jet of steam which is made to combine with the combustion gases to produce a larger jet which carries the combustion gases out of 35 the stack and at the same time so reduces the pressure in the stack that the proper draft in the combustion chamber results. To this end I give the stack the shape of a Venturi tube and place within the same, and coaxial 40 therewith, a second Venturi tube of very much smaller diameter; the second Venturi tube serving as a nozzle to deliver a jet in the upward direction just below the contracted portion of the stack. A small pipe 45 that carries steam or other gaseous fluid under high pressure, discharges a jet upwardly into the lower end of the small inner Venturi tube, at a point below the contracted part in the latter. This steam, under high pressure and 50 of low volume, enters the inner Venturi tube

at high velocity, causing a partial vacuum in the lower end of this Venturi tube; whereby combustion gases are driven into the lower end of the inner Venturi tube, mix with the steam, and are carried upwardly. The inner Venturi tube increases gradually in cross-sectional area from the contracted portion toward the top. Therefore the velocity of the gaseous mixture decreases as it rises in the inner tube, and the mixture spreads out 55 into a larger space. Therefore, as the gaseous mixture reaches the upper end of the inner Venturi tube, the volume thereof is relatively large and the pressure and velocity 60 are moderately low.

In other words, a small jet, under high pressure, and at high velocity enters the lower end of the inner Venturi tube which then delivers into the contracted portion of the stack a large jet under relatively low 65 pressure and moving at a relatively low speed. This large, slowly moving jet creates a partial vacuum in the lower portion of the stack, in the space surrounding the inner Venturi tube, and causes the gases in this space 70 to be drawn up and discharged out of the top of the stack.

By constructing the stacks in accordance with my invention, I find that they need not be more than eight feet long instead of 80 thirty-five feet long, as heretofore, and need not weight more than about three hundred pounds. So far as the consumption of steam to produce the draft is concerned, I find that there is in many cases less than one-fifth of 85 that heretofore used, averaging less than six per cent of the steam generated.

The various features of novelty whereby my invention is characterized will herein- 90 after be pointed out with particularity in the claims; but, for a full understanding of my invention and of its objects and advantages, reference may be had to the following detailed description taken in connection with the accompanying drawing, wherein:

Figure 1 is a view, partly in elevation and partly in section, showing a fragment of a boiler having one of my improved stacks; and Fig. 2 is a top plan view of the stack.

Referring to the drawings, 1 and 2 repre- 100

sent frustoconical shells, arranged in axial alignment with each other, the large end of the lower shell being at the bottom and the large end of the upper shell being at the top; 5 and there being a short cylindrical shell 3 connecting the shells 1 and 2 and constituting the contracted neck of the Venturi tube formed by the three shells. This Venturi tube takes the place of the usual stack rising 10 from a boiler 4 or smoke chamber associated with the boiler.

In the lower half of the stack is a second Venturi tube of comparatively small diameter. In the arrangement shown, this second 15 or inner Venturi tube consists of a short lower section in the form of a bell 5 and a long upper section 6 opening out of the top of the bell and increasing gradually in diameter toward the upper end. The diameter of the 20 open bottom of the bell is much greater than the diameter of the lower end of the tubular section 6, so that the juncture of the bell and the section 6 forms the contracted neck of the inner Venturi tube. The inner Venturi 25 tube is coaxial with the stack and its upper end lies just below the contracted portion or neck of the outer Venturi tube or stack.

The inner Venturi tube may be supported in fixed relation to the stack in any suitable 30 way. In the arrangement shown, the inner tube has near its upper end a plurality of radial arms 7 projecting therefrom and welded or otherwise secured at their outer ends to the surrounding stack wall.

35 Extending up into the bottom of the bell 5 a short distance is a small pipe 8 so positioned that fluids discharged therefrom will be delivered in the upward direction along the long axis of the inner Venturi tube. In 40 actual practice this pipe may be an ordinary quarter-inch pipe. When steam at a pressure of from one hundred ninety pounds to two hundred and fifty pounds per square inch is discharged from this pipe at high velocity, it 45 creates a partial vacuum in the bell, causing combustion gases or smoke to enter the bell and mix with the steam. As the mixture rises it spreads laterally within the enlarging tube, and the velocity and pressure decreases. The 50 mixture issues from the upper end of the inner Venturi tube in the form of a jet of large volume at a velocity and pressure that are lower compared with the velocity and pressure of the steam jet. This large, secondary jet creates a partial vacuum in the 55 space 9 within the stack and surrounding the inner Venturi tube which induces the necessary draft in the combustion chamber of the plant.

60 While I have illustrated and described with particularity only a single preferred form of my invention, I do not desire to be limited to the exact structural details thus illustrated and described; but intend to cover all forms 65 and arrangements which come within the

definitions of my invention constituting the appended claims.

I claim:

1. In combination, a smoke stack in the form of a Venturi tube, a second, inner Venturi tube smaller in cross-sectional area than the stack fixed within and coaxial with the stack, said inner Venturi tube consisting of a long upper section tapering only slightly from the smaller end toward the top and a 75 short flaring lower section or bell, the upper end of the inner Venturi tube being positioned in the vicinity of the contracted part of the stack and the lower end of the inner Venturi tube opening out into the stack, and 80 means to produce within the inner tube and below the contracted part thereof an upwardly-directed jet.

2. In combination, a smoke stack in the form of a Venturi tube, a second, inner Venturi tube fixed within and coaxial with the stack, the upper end of the inner Venturi tube being positioned in the vicinity of the contracted part of the stack, said inner Venturi tube consisting of a long upper section 90 the diameter of whose upper end is much smaller than the diameter of the contracted part of the stack and a short flaring lower section or bell opening out into the stack and having a diameter which is only a small 95 fraction of the diameter of the surrounding part of the stack, and a steam pipe of small diameter coaxial with the inner Venturi tube extending up into the lower end of the latter and having an open upper end positioned below the contracted part of the inner Venturi tube.

In testimony whereof, I sign this specification.

HOWARD M. WOLF.
